ASH-RETAINING CIGARETTE HOLDER

Wallace E. Walden, Domingo, N. Mex.

Application December 10, 1936, Serial No. 115,218

1 Claim. (Cl. 131—51)

This invention relates to a holder or the like for cigarettes and it aims to provide a novel construction wherein the ashes resulting from combustion will be retained within the holder and wherein a cigarette cannot ignite adjacent articles with which it may contact, yet permitting free draft for combustion purposes, and to further provide a construction, which although holding the cigarette, will more closely than heretofore, simulate the direct engagement of the cigarette by the lips and give a more natural and enjoyable smoke.

The more specific objects and advantages will become apparent from a consideration of the description following taken in connection with accompanying drawing illustrating an operative embodiment.

In said drawing:—

Figure 1 is a view of the invention in side elevation,

Figure 2 is a view of the invention in central longitudinal section, showing a cigarette in place therein,

Figure 3 is a side elevation of the screen section detached, and

Figure 4 is a view in perspective on an enlarged scale of the reinforcing members for the screen section.

Referring specifically to the drawing wherein like reference characters designate like or similar parts, a cigarette of conventional form is disclosed at 10 and my improvements comprise a mouth piece 11 and a screen enclosure or cage 12, said parts 11 and 12 being detachably inter- 25 fitted, completely enclosing the cigarette and being of the same length collectively, as the cigarette to insure initial operative positioning of the parts, and their relation to the cigarette.

Said mouth piece or holder 11 may be made of any desired material, for instance rubber, rubberized fabric, etc. It has a bore 13 therethrough and the adjacent mouth engaging portion of the holder as at 14 is relatively thin. When the holder is in the mouth, the tongue may touch 40 the inner end of the cigarette and tobacco therein.

Said bore at the outer portion of the holder is enlarged as at 15. Externally the holder may be

of any desired shape such as quadrangular or otherwise polygonal in cross section, to guard against rolling.

The screen section 12 is preferably made from metallic screen material of twenty meshes to the lineal inch. It is cylindrical, closed at one end and at the inner end has reenforcing and securing elements 16 of U-shape, clinched thereto, reinforcing the edges, and such elements are relatively close together. The parts are so constructed that the elements 16 are slightly farther apart than the diametrically opposite portions of the wall in the enlargement 15 so that when the sections 16 are connected with the holder, by relative sliding movement, there will be compression for movement of the elements 16 toward each other to the end that they will have a tendency to expand within the enlarged portion 15 and thus better separately connect the parts.

It will be realized that the cigarette may be ignited through the cage or screen 12 but that the meshes are of such a size as to collect the ashes and retain them. Also it will be realized that the meshes will not permit the fire or flame to pass therethrough, which is highly advantageous in reducing the fire hazard, since contact of the screen or device, should it fall out of the hand and engage adjacent structure, will not ignite it.

Various changes may be resorted to provided they fall within the spirit and scope of the invention.

I claim as my invention:—

A device of the class described comprising a tubular screen element adapted to surround a cigarette, and a holder for the cigarette and screen element, said holder having a bore large enough to hold the cigarette, said bore having an enlarged portion, one end of said screen being disposed in said enlarged portion and compressed, said end having a plurality of reenforcing elements of U-shape surrounding the same and being in spaced relation, said elements being secured to the screen, and said holder being relatively thin at the mouth engaging portion, and being flexible so as to simulate the yielding of the end of the cigarette, in the mouth.

WALLACE E. WALDEN.
